UNITED STATES PATENT OFFICE

2,322,998

ROAD GRADER

Franklin E. Arndt, Galion, Ohio, assignor to The Galion Iron Works & Manufacturing Company, a corporation of Ohio

Application March 12, 1940, Serial No. 323,586

9 Claims. (Cl. 37—157)

My invention relates to a road grader, and one of its objects is the provision of improved and efficient means for mechanically adjusting the moldboard of the road grader to a steep bank-cutting position at either side of the machine and holding the moldboard in such adjusted position during operation.

A further object of the invention is the provision of mechanism for leaning the wheels of a road grader comprising arcuate gear with limit stops at the ends thereof to prevent the overrunning of an actuating pinion.

Another object of the invention is the provision of improved mechanism for connecting the front end of the drawbar of a road grader to the front end of the main frame with such flexibility as to facilitate the adjustment of the drawbar from a position under the main frame to an upright position at either side thereof.

A further object of the invention is the provision of improved and efficient mechanism in the steering unit of the road grader.

Another object of the invention is the provision of improved and efficient circle mechanism for carrying the grader blade and adjusting the inclination thereof relative to the path of travel of the machine.

A further object of the invention is the provision of improved and efficient means for effecting shifting of the rear end of the vehicle frame relative to the rear axle of the road grader.

Another object of the invention is the provision of improved resiliency for the support of the operator at the rear end of the machine.

A further object of the invention is the provision of improved resilient counter-balancing mechanism effective not only when the grader blade is under the machine but also when it is in bank sloping position at either side of the machine.

More particularly it is the object of the present invention to provide hangers each comprising a tube open at both ends with a rod sliding entirely through the same and held in adjusted position by a pin inserted through an aperture in the tube and one of the series of apertures in the rod.

It is also the object of the invention to provide in a bank sloping machine, a longitudinal rock shaft connected by a radial arm at its front end through a link to one side of the rear end of the drawbar for co-operation with links each extensible in length for adjusting the grader blade to an upright position with its cutting edge spaced from the path of travel of the machine.

A further object of the invention is the provision of a rock shaft pivotally mounted on the vehicle frame of the road grader in such a low position as to permit the outer end of a radial arm connected to the rock shaft to be swung to such an elevated position as to elevate the drawbar from the roadway as to enable co-operation with extensible hangers to adjust the moldboard or grader blade from a position under the machine to a steep bank sloping position with ample clearance for the heel of the blade when so adjusted.

Other objects of the invention will appear hereinafter, the novel features and combinations being set forth in the appended claims.

In the accompanying drawings,

Figs. 1 and 2, placed end to end, show a side elevation of the road grader embodying my improvements;

Fig. 3 is a diagrammatic view illustrating the operation of the steering unit;

Fig. 4 is a sectional plan view taken on the line 4—4 of Fig. 1;

Fig. 5 is a sectional elevational view taken on the line 5—5 of Fig. 1, looking in the direction of the arrows;

Fig. 6 is a sectional plan view taken on the line 6—6 of Fig. 1;

Fig. 7 is a bottom plan view of the circle mounted on the rear end of the T-shaped drawbar;

Fig. 8 is a sectional elevational view taken on the line 8—8 of Fig. 7, looking in the direction of the arrows;

Fig. 9 is a sectional view taken on the line 9—9 of Fig. 7, looking in the direction of the arrows;

Fig. 10 is a rear elevational view of the road grader with the grader blade in steep bank-cutting position, with the heel of the cutting blade entirely outside of the path of travel of the machine and with the delivery edge of the moldboard inside of the path of travel of the adjacent rear wheel;

Fig. 11 is a rear view of the machine with the moldboard in its entirety outside of the path of travel of the machine with the cutting edge in substantially upright position;

Fig. 12 is an enlarged rear view of the rear wheel leaning mechanism and mechanism for shifting the rear end of the frame laterally relative to the rear wheels;

Fig. 13 is an enlarged side elevation to illustrate the mechanism for effecting leaning of the rear wheels and the mechanism for effecting lateral shift of the rear end of the vehicle frame;

Fig. 14 is a view to illustrate that the lowered

axis of the rock shaft of the laterally shifting mechanism enables the outer end of the radial crank arm to be lifted to such an elevated position as to be above a horizontal plane extending through the actuating rock shaft; and

Fig. 15 is a sectional elevation of a portion of Fig. 2 looking in the direction of the arrows 15—15.

As shown in Fig. 2, the main supporting frame 15 is upwardly arched and is supported at its rear end on its wheels 16 and at its front end on the wheels 17 (Figs. 1, 4 and 5). The frame 15 is shown in Fig. 11 as comprising spaced-apart longitudinal side beams 18, 18, and as shown in Fig. 2 these spaced-apart side beams are connected by the tubular cross braces 19, 20 and 21. As shown in Figs. 1 and 2, the front and rear wheels are preferably of metal so that the rims thereof will be sufficiently thin to be able to dig into the road surface when the wheels are leaned in such direction as to resist lateral skidding when the moldboard is in steep bank-cutting position, such as that shown in Fig. 10 or Fig. 11, and under operation by movement of the whole machine along the roadway, as will be more fully explained hereinafter.

The machine shown in the accompanying drawings includes mechanism for the steering of the front wheels, the leaning of the front wheels, the leaning of the rear wheels, the shifting of the rear end of the main frame laterally relatively to the rear wheels, the shifting of the moldboard laterally and movement thereof to bank sloping position, and the adjustment and locking of the circle shown in Fig. 7. All of the controls extend to a single operator's station or platform 22 at the rear end of the machine, as shown in Figs. 2, 10 and 11. Although I have shown in the accompanying drawings a pull type of road working machine comprising a tongue 23 to the front end of which is adapted to be connected a pulling tractor, it should be understood that my improvements hereinafter described are also useful in a power grader comprising a power plant connected to the rear traction wheels for moving the entire machine along the roadway.

The front wheel steering mechanism comprises a driving sprocket 24 meshing with a chain 25, the ends of which are connected by means of links 26 and 27 to the bolster 28 mounted on the front axle 29. As shown in Fig. 4, the rear ends of the links 26, 27 have eyes 30, 31 which interloop the U-bolts 32. As shown in Figs. 4 and 5, the U-bolts 32, 33 extend through openings in the plates 34, 35 and 36, 37 on opposite sides of the channels 38, 39 of the bolster 28. The lower ends of the channels 38, 39 are bolted to the angle irons 40, 41, and the plates 34, 35 and 36, 37 are at the same time bolted to the angle irons 40, 41. The bolster has surmounted thereon a cap 42 which has a central opening in its top. It will thus be seen that the bolster 28 and the front axle-tree form a single rigid structure for supporting on the wheels 17, 17 the front end of the vehicle frame 15.

The tubular tongue 23 has rigidly secured to the rear end thereof a vertical plate 43. A tube 44 is secured as by welding to the rear end of the plate 43, and plates 45, 46 are welded to the lower and upper edges of the plate 43 and the lower and upper ends of the tube 44. The plates 45 and 46 are provided with openings which register with openings in the cup bearing 47 and the bracket bearing 48. The cup bearing 47 is secured to the upper horizontal flange of the angle iron 40. The

bracket bearing 48 is secured rigidly to the cap 42 of the bolster 28. A bearing rod 49 may be dropped through the bracket bearing 48, the opening in the plate 46, the tube 44, and the opening in the plate 45 with the lower end of the rod 49 in the cup bearing 47. The rod 49 may then be pinned to the bracket bearing 48.

Fig. 3 shows diagrammatically the advantage of the pivot rod 49 being placed in advance of the center of the steering post 50. The pulling tractor illustrated in dotted lines at 51 exerts a straight-line pull through the tongue 23 on the pivot 49 but at the same time there is a component of pulling force represented by the line 52 extending forwardly from the center 50 of the steering post. The pull on the pivot point 49 aids in steering the steering unit in an anti-clockwise direction, as viewed in Fig. 3.

When the steering wheel 53 at the rear of the machine (Figs. 2, 10 and 11) is rotated, the shaft 54 will transmit rotary motion through the universal joints 55, 56, 57 and the links 58, 59 to the worm gearing in the casing 60 and thus rotate the sprocket 24 meshing with the chain 25 and thereby swing the tongue 23 in one direction or the other relatively to the front wheels. A counterbalancing spring 61 is connected to the tongue 23 intermediate its ends and also to a swiveled connection 62 at the top of the post 50, as shown in Fig. 1.

In order to effect adjustment of the leaning of the front wheels 17, the crank 63 (Figs. 10, 11) is so manipulated as to secure rotation of the links 64, 65, 66, 67, 68, as shown in Figs. 1, 2 and 5. The rotation of these links will rotate the worm 69 and the worm wheel 70 with which it meshes. Keyed to the worm wheel 70 is a pinion 71 which meshes with the arcuate rack 72, as shown in Fig. 5. The worm 69 and worm wheel 70 are mounted in the casing 73 as shown in Figs. 4 and 5.

The shaft 74 to which the worm wheel 70 and the pinion 71 are keyed, extends rearwardly so that the pinion 71 meshes with the underside of the arcuate rack 72. As shown in Fig. 5, the arcuate rack 72 is secured to and suspended from the cross link 75, the ends of which are pivoted at 76, 76 to the upper ends of the arms 77, 77, the latter being pivoted on longitudinal axes at 78, 78 to the ends of the axle-tree 29. The lower ends of the arms 77, 77 carry the axles on which the wheels 17, 17 are journaled.

It can readily be seen by referring to Fig. 5 that when the worm 69 is turned, the wheels 17, 17 will be leaned in either direction while remaining in parallelism. It should be particularly noted that the bracket 79 which carries the rack 72 on its lower side, has its end portions curved at 80, 80 with the inner under surfaces approximately conforming to the circumference of the pinion 71. The arcuate extensions 80, 80 prevent the pinion 71 from overrunning the arcuate rack 72 to such an extent as to move from under the bracket 79. In other words, the arcuate extensions act as limit stops as to the leaning of the wheels 17, 17 because when the pinion 71 moves against the under sides of the arcuate extensions 80, 80, the latter will act as limit stops positively preventing the pinion 71 from being rotated any farther, if any of its teeth are still in mesh with any of the teeth of the arcuate rack. If the pinion 71 runs entirely out of mesh with the arcuate rack 72, such arcuate extensions 80, 80 will still act as limit stops because they will merely permit the outer ends of the teeth 71 to

slide along the bottom arcuate surfaces of the extensions 80 without making any progress, but nevertheless when the pinion 71 is reversed its teeth will immediately re-mesh with the arcuate rack 72 so that the leaning of the wheels 17, 11 may be reversed. When the moldboard is operated in steep bank-cutting position, the leaning of the front wheels will be held in adjusted position by reason of the self-locking nature of the worm gearing 69, 70. It will thus be seen that irrespective of the relative positions of the pinion 71 and arcuate rack 72 the front wheels will be able to resist the lateral thrust exerted on the machine during operation of the moldboard along a steep bank at one side of the path of travel of the machine.

The drawbar 81 as shown in Figs. 1 and 2, comprises a narrow elongated front end 82 connected by an intermediate curved portion to a rear horizontal T-shaped frame which carries the circle 83. As shown in Fig. 7, the drawbar may comprise two angle irons 84, 84 welded together with their horizontal flanges at the bottom so that a plate 85 may be welded along the upper edges of the angle irons and slotted at its forward end portion to slide down over and be welded to the vertical legs of the angle irons.

The front end of the drawbar is provided with a universal connection to the steering post 50. The lower end of the steering post 50 is provided with a plate 86 which is adapted to rest on the circular support 87 at the upper end of the cap 42 as shown in Fig. 5. Passing through the sides of the steering post 50 a short distance above the plate 86 are the legs of a U-bolt 88, the free ends of which are threaded to receive the nuts 89, 89. The U-bolt 88 interloops the eye-bolt 90 the forward end of which is adapted to fit into an arcuate recess 91, as shown in Fig. 6. The rear end of the eye-bolt 90 is provided with a shank 92 which is swiveled in the socket 93 which is secured to the bottom of the front end of the drawbar. The rear end of the shank 92 is threaded at 94 to receive a nut 95 which may be locked in adjusted position with the flange 96 on the shank 92 resting against the forward end of the socket 93. It will thus be seen by referring to Figs. 1 and 6 that the drawbar 81 may turn on its swiveled connection at 92, 93 relatively to the steering post 50 and moreover the drawbar 81 may swing laterally upon an upright axis at 91 along the U-bolt 88. Furthermore, the drawbar 81 may swing up and down while the eye-bolt 90 is pivoted on the U-bolt 88 and in the arcuate recess 91.

It should be particularly noted that the steering post 50 is rigidly connected to the forward ends of the channel beams 18, 18 and therefore to the forward end of the main frame. The universal connection at the forward end of the drawbar 81 is therefore in reality connected to the front end of the main frame and the parts are so closely related that no relative vibration between them is possible irrespective of the various high lift grading positions to which the grader blade has been adjusted.

The recess 91 is therefore an important feature because it confines the eye-bolt 90 against vibration relative to the U-bolt 88 and yet the desired universal connection is maintained. It should also be noted by referring to Figs. 1 and 5 that great flexibility between the steering unit and the main frame is provided for the travel of the steering unit over irregular ground surfaces but nevertheless the drawbar 81 may always be main-

tained in rigid connection to the main frame during grading operations and bank sloping operations.

The circle 83, as shown in Figs. 2 and 7, carries the moldboard 97 by means of the arms 98, 98. Mounted on the cross-piece 99 at the rear end of the drawbar are circumferentially spaced retaining plates 100, 101 as shown in the bottom plan view of Fig. 7. Abutments 102, 103 are welded to the bottom of the cross-piece 99. Slotted wedge plates 104, 105 are located between the abutment plates 102, 103 and the slidably abutment plates 106 are each located on top of the plates 100 and 101. Fig. 9 is a sectional view taken on the line 9—9 of Fig. 7.

The plates 100 and 101 are in fixed relation to the cross-piece 99 when the bolts 107, 107' are tightened in place. The plates 100, 101 are adapted to overlap the flange 108 of the circle but the latter is free to slide along these plates 100 and 101 when the circle rotating mechanism is operated. The plates 106 have enlarged openings for the bolts 107, so that they may engage the inner edges of the flange 108 of the circle. This is effected by means of the wedges 104, 105 which engage the inner edges of the plates 106 when the bolts 107 are loosened. That is to say, when the bolts 109, 109 are loosened as well as the bolts 107, 107', the wedges 104, 105 may be moved tangentially of the center of the circle along the abutments 102, 103, thereby forcing the outer edges of the plates 106 against the inner edges of the flange 108. After this has been done the bolts may be re-tightened.

The rotatable circle carries a segmental arcuate rack 110 with which meshes the pinion 111 as shown in Fig. 7. The pinion 111 is connected to the lower end of a shaft, the upper end of which is connected by means of worm gearing through the link mechanism 112, gearing 113 and a flexible shaft 114 to the gear mechanism in the casing 115 of Fig. 11 for actuation by means of the lever 63 when the latter is set in a predetermined position. This mechanism operated by the lever 63 may be such as that illustrated in the patent to Arndt, No. 2,012,463, granted Aug. 27, 1935, for an improvement in Road planer or drag.

Mechanism for locking the circle in adjusted position comprises a pawl 116 which is pivotally mounted on the drawbar frame members 84, 84 for up and down pivotal movement on the axis 117 shown in Fig. 8. An arm 118 extends from the pawl 116 into position for connection by means of a restoring spring 119 to the bracket 120.

The casting 121 is provided with a journal bearing 122 for the transverse shaft 117. An arcuate extension 123 overlaps the flange 108 as shown in Fig. 8. An abutment plate 106' engages the cylindrical abutment surface 124 at the inner edge of the circle 83 adjacent the flange 108. It will thus be seen that the abutment plates 106, 106, 106' engage the inner edge or cylindrical abutment surface 124 of the flange 108 so as to properly hold the circle for circular adjustment in fixed relation to the T-shaped drawbar. The bracket casting 121 as well as the abutment plate 106' are provided with registering openings for receiving the bolts 125, 125. The loosening of these bolts so as to free the abutment plate 106' facilitates adjustment of the abutment plates 106, 106 when the bolts 107, 107 and 107', 107' are loosened and the wedges 104 and 105 operated while the bolts 109, 109 are released. After adjustment of the circle has been made with respect to the T-shaped drawbar, the bolts are re-tight-

ened so as to hold the plates 106, 106, 106' in close fitting relation to the cylindrical abutment surface 124 with the retaining plates 100, 101 and 123 overlapping the flange 108. Inasmuch as Fig. 7 is a bottom plan view, it can readily be seen that the circle when in adjusted position is supported from the T-shaped drawbar by means of the retaining plates 100, 101 and 123 which are extended under the flange 108.

The spring 119 acts on the arm 118 to move the toothed pawl 116 into mesh with the arcuate rack 110, as shown in Figs. 7 and 8. By pulling the handle 126 at the operator's station (Fig. 2), the links 127, 128 may be actuated so as to move the bell crank 129 on its pivot 130 and thereby exert a forward pull on the link 131 which is connected to the upper end of the lever 118. In this manner the pawl 116 is pulled down and released from the arcuate rack 110.

While the operator holds the pawl 116 released by pulling on the handle 126 he may adjust the lever 63 (Fig. 10) into such position as to enable him to operate the links 132, 133 so as to secure transmission through the gearing 113 by actuation of the worm gearing in the casing 134 and thus effect rotation of the pinion 111 to in turn rotate the circle 83. In this manner the operator at his station may swing the moldboard 97 to a desired angle relative to the path of travel of the machine, while the moldboard remains under the machine as shown in Fig. 2, in road grading position.

The moldboard may be adjusted in elevation and in inclination transversely of the roadway by means of structure comprising the extensible hangers 135, one located on one side of the machine and the other located on the opposite side of the machine. Each hanger comprises a rod 136, the lower end of which is connected by means of a ball and socket joint 137 to a ball holder 138 which is secured to one end portion of the rear cross-piece 99 of the T-shaped drawbar. The rod 136 is slideable into and entirely through the tubular member 139 of the hanger 135 (Fig. 2). The hanger 135 is adjustable in length by reason of the fact that the rod 136 has a series of apertures 140 any one of which is adapted to register with an aperture through the lower end of the tubular member 139. A pin 141 is inserted through the registering apertures to hold the hanger 135 at adjusted length.

To the upper end of the tubular member 139 of the hanger 135 is secured a socket 142 for receiving a ball which is mounted on the stem 143, this stem being in turn mounted on a radial arm 144 which extends outwardly and laterally from the rock shaft 145. This rock shaft is journaled in the bearing 146 which is secured to the bracket 147 extending laterally from the main frame a substantial distance. The rear end of the rock shaft 145 is journaled in the bearing 148 mounted on the upright 149 of a U-shaped frame secured to the spaced-apart channel beams 18, 18 by means of the cross piece 150. It should be understood that a hanger similar to that designated 135 in Fig. 2 is also located on the opposite side of the machine and connected to a radial arm at the forward end of a rock shaft similar to that designated 145 (see Fig. 14).

The rear end of the rock shaft 145 is connected to worm gearing in the casing 151 and a large wheel 152 as shown in Fig. 11 is connected to such worm gearing to enable the operator at the operator's station to rock the shaft 145 and thus lift or lower the hanger 135. The hanger on

that side of the machine opposite to that shown in Fig. 2 is provided with a perforated rod capable of extending entirely through a tubular member, and such hanger on the opposite side of the machine is provided with a pin for holding the hanger at adjusted length. The hanger on the opposite side of the machine may be operated by the wheel 153 connected to worm gearing in the casing 151', which is mounted on the upright 149' of the U-shaped frame mounted on the channels 18, 18. By referring to Fig. 11, it can readily be seen that the rock shafts 145 on opposite sides of the machine are each spaced substantial distances from the sides of the main frame because of the brackets 147 which extend laterally from the main frame, as illustrated in Fig. 14.

Extending longitudinally of the rear portion of the main frame is a rock shaft 154 which at its outer end has a radial crank arm 155 which is provided at its outer end with a ball and socket joint connection 156 with one end of the link 157, the other end of which is connected by the ball and socket joint 158 to the ball carrier 138 mounted at one side of the rear end portion of the drawbar. The front end of the rock shaft 154 is journaled in the bearing 159 which is supported on the cross-piece 160 secured to and extending between the channels 18, 18 of the main frame.

The rear end of the rock shaft 154 is journaled in the bearing 161 mounted on the sub-frame 162 which is secured to and extends transversely between the channels 18, 18 of the main frame.

The rear end of the rock shaft 154 is connected to interlocking worm gearing in the casing 163. A wheel 164 is connected to a worm in the gear casing 165 (Fig. 10). When the wheel 164 is rotated by the operator at his station the rock shaft 154 may be rotated in one direction or the other to swing the arm 155 upwardly toward one beam or the other of the spaced-apart beams of the main frame. As shown in Fig. 14, the crank arm 155 may be rotated so that the ball and socket joint 156 may be projected beyond either side of the main frame. In fact, the radial arm 155 may be rotated through an angle of more than one hundred and eighty degrees so that the ball and socket joint 156 may be elevated to such a position that it lies in or above a horizontal plane extending through the horizontal lower edges of the channels 18, 18.

By adjusting the hanger 135 so that it will be of maximum length on that side of the machine from which the arm 155 is moved and by adjusting the hanger 135 on the other side of the machine to a minimum length, the rotation of the rockshafts 145 may co-operate with the rotation of the rock shaft 154 to move the moldboard into the steep bank-cutting position shown in Fig. 11.

That is to say, by providing hangers of the construction shown at 135 in Fig. 2 and locating them substantially beyond the sides of the machine, they may be capable of cooperating with the crank arm 155 having the wide angle of the movement above described, to move the moldboard entirely out beyond the path of travel of the machine as shown in Fig. 11. Since the hangers are provided with tubular elements 139, with rods 136 capable of being moved entirely through the tubular members and having the arm 155 swingable through such a large angle in either direction, the moldboard may be adjusted to its upright position shown in Fig. 11, at either side of the machine. So also the moldboard may be adjusted to the position shown in Fig. 10 on the left-

hand side of the machine as well as on the right-hand side thereof. In fact the hangers 135, 135 may be adjusted to such lengths that the moldboard may be adjusted from the road grading position shown in Fig. 2 to the steep bank-sloping position shown in Fig. 10 without changing the length of either hanger. However, before the moldboard is moved to its upright position shown in Fig. 11, the upper hanger is shortened to its minimum length and the lower hanger is lengthened to its maximum length.

Spaced-apart rearward extensions 166, 167 are provided with guides for the rear axle-tree 168 comprising the spaced-apart angle irons 169, 170. Between these angle irons and secured thereto is located a casing 171 for worm gearing which is connected to the link 172 which extends upwardly and transversely, as shown in Fig. 10, to the upright rotary rod 173 journaled in the bearings of the brackets 174, 175 which are mounted on the rear side of the gear casing 151'. A crank 176 is connected to the upper end of the rotary rod 173 (Fig. 10) and when this crank is turned the worm gearing in the casing 171 may be operated to rotate the pinion 177 which extends rearwardly of the cross-piece 170 of the rear axle-tree 168.

The pinion 177 meshes with an arcuate rack 178 which is mounted on the cross-piece 179. At the ends of the arcuate rack 178 are located arcuate limit stops 180 and 181 to prevent the pinion 177 from overrunning the ends of the rack 178. The construction and operation are similar to those described in connection with the structure mounted on the front wheel steering unit for leaning the front wheels, as shown in Fig. 5.

As shown in Figs. 10 and 12, rotation of the pinion 177 will move the rack 178 bodily with the cross-piece 179 because the frame of the rack 178 is bolted at 182, 183 to the cross-piece 179.

The ends of the cross-piece 179 are pivotally connected at 184, 185 to the upper ends of the arms 186, 187 which are pivoted at 188, 189 on longitudinal axes to the outer ends of the arcuate extensions 190, 191 at the outer ends of the rear axle-tree 168. The arms 186, 187 carry the axles on which the wheels 16, 16 are journaled. It will thus be seen that the movement transversely of the machine of the cross-piece 179 will adjust the leaning of the rear wheels but the arcuate limit stops 180, 181 will limit the leaning of the wheels and prevent the pinion 177 from overrunning the rack 178. The worm gearing in the casing 171 is self-locking and consequently when the operator releases the crank 176, the leaning of the rear wheels will be locked in adjusted positions.

As shown in Figs. 2, 12 and 13, a rack bar 192 is mounted on the cross-piece 169. Secured to the main frame is a worm gear casing 193. Connected to the worm gear in the worm gear casing 193 is a spur gear 194 in mesh with the rack bar 192. Connected to the worm gearing in the casing 193 is a link 195 which extends upwardly for connection to the lower end of the rod 196 which is journaled in the brackets 197, 198 mounted on the rear side of the worm gear casing 151. By means of the crank 199 connected to the upper end of the rod 196, the operator at the operator's station may drive the spur gear 194 to cause the main frame to travel along the rack 192 and thus adjust the rear end of the main frame along the rear axle-tree and relative to the rear wheels 16, 16.

As shown in Fig. 2, the operator's platform 22 is pivoted at 200 to the cross-piece 150. The rear end portion of the operator's platform 22 is mounted on spaced-apart springs 201 and these springs in turn are mounted on the inverted U-shaped frame 202 as shown in Figs. 10 and 11. It should be particularly noted, however, by referring to Fig. 2 that the frame 202 is mounted on an angle iron 203 which is secured to the spaced-apart rearward extensions 166, 167. Therefore when the rear end of the main frame is shifted relatively to the rear wheels, the frame 202 remains in fixed relation to the main frame. In other words, when the main frame is shifted laterally relatively to the rear axle-tree, the operator's platform being in fixed relation to the main frame also moves laterally along the rear axle-tree.

It should be particularly noted that the arcuate extensions 190 and 191 at the ends of the rear axle-tree 168 are for the purpose of lowering the axles on which the rear wheels 16, 16 are journaled. The spacing between the rear axle-tree and the cross-piece 179 is preserved by inclining downwardly the outer ends of the cross-piece 179 as shown in Figs. 10 and 11. The use of the arcuate extensions 190, 191 to lower the axles on which the wheels 16, 16 are journaled, enables the front wheels and rear wheels to be interchangeable. That is to say, by having the centers of the rear wheels at the same distances above the supporting surface as the centers of the front wheels, the front and rear wheels are interchangeable and the frame spacing above the supporting surface will be approximately the same at the front end of the machine as at the rear end. At the front end of the machine the front axle-tree 29 is located at a certain distance from the ground surface, this being approximately from the center of the front wheels 17, 17 to such ground surface, as shown in Fig. 5. At the rear end of the machine in order to preserve this spacing from the ground surface, the rearward extensions 166, 167 from the main frame are at an elevation approximately equal to that of the center of rotation of the rear wheels.

It would be undesirable to omit the arcuate extensions 190, 191 and have the rear axle-tree 168 extend straight across between the centers of the rear wheels because not only would the rearward extensions 166, 167 become too low for the clearing of obstacles on the ground surface, but the rear end of the main frame would become unduly lowered for high lift adjustments of the moldboard. In other words, by providing the arcuate extensions 190, 191, ample clearance of the extensions 166, 167 from the ground surface is preserved, and moreover the rear end of the main frame is kept at sufficient elevation so that the rock shafts 145 and 154 will be at sufficient elevations to provide ample clearance for the heel of the moldboard when the latter is moved to steep bank sloping positions.

It should be noted that a ball holder similar to that designated 138 in Fig. 2 is also located at the opposite end of the cross piece 99. The link 157 may be connected to the ball holder 138 on one side of the rear end of the drawbar 81 or on the other side of the rear end thereof. When the moldboard is in steep bank-cutting position at either side of the machine it is preferable to have the link 157 act as a suspension rod.

As shown in Fig. 5, the post 50 is provided with

a depending bearing 204 in which is journaled the vertical shaft 67. In a circular groove at the lower end of the journal bearing 204 is a washer 205 on which is supported the cup-shaped washer 206.

If desired the washer 205 may be in two semi-circular sections easily placed in the circular groove when the cup 206 is slid up along the journal bearing 204. When the cup 206 is permitted to drop down over the semi-circular sections of the washer 205, the latter is locked to the lower end of the bearing 204. Further locking may be effected by passing a wire through holes in the depending skirt of the cup 206 and extending such wire transversely under the lower end of the bearing 204 and twisting together the free ends of the wire. By means of this arrangement the steering wheel unit may be removed from the main frame when desired.

This structure permits the front end of the main frame to be maintained in adjusted position during operation of the moldboard while the steering wheel unit is free to move up and down and tilt in opposite directions to the extent allowed by the cup 206 bumping against the bottom of the ring 87. In other words, the steering wheel unit has great flexibility relative to the main frame as it travels over rough ground which has not as yet been acted on by the moldboard.

Upright counterbalancing springs 207 are mounted at the sides of the vehicle frame and the lower ends of these springs are connected at 208 to anchorages which project laterally from the bottom of the vehicle frame as shown at 209 in Figs. 2 and 15. Segmental sheaves 210 are secured to the shafts 145 to rotate therewith. Flexible connections in the form of chains 211 extend between the segmental sheaves 210 and the upper ends of the springs 207, respectively located between its adjacent rock shaft 145 and the vehicle frame in position to enable the springs 207 to counterbalance a part of the weight of the drawbar and moldboard. It should be noted that the sheaves 210 constitute grooved cams on the rock shafts 145. The chains 211 are connected to these cams and reaved along the grooves thereof, as shown in Figs. 2 and 15. The springs 207 connect the rear portion of the vehicle frame to the chains 211 at the inner sides of the rock shafts 145 in opposition to the radial arms 144 to counterbalance the weight exerted by the drawbar and grader blade on the hangers 135.

It can readily be seen by comparing Fig. 2 with Fig. 10 that the arm 144 must be moved through a wide angle in order to permit movement of the moldboard from road grading position to steep bank cutting position. By locating the springs 207 at the sides of the machine in upright positions they may be made of sufficient length to enable them to be effective as counterbalancing springs both when the moldboard is in the road grader position shown in Fig. 2 and when the moldboard is in the steep bank cutting position shown in Fig. 10. When the arm 144 is moved through such wide angle the segmental sheave or grooved cam 210 is moved through a like angle and the spring 207 is stretched out until its upper end is at the elevation of the rear end portion of the rock shaft 145. In addition to locating the counterbalancing springs at the sides of the vehicle frame so that they may be made of sufficient length to be most efficient in a steep bank cutting machine, the springs are in loca-

tions where they will not interfere with any of the operating extensions between the operator's station and the adjusting mechanisms on the drawbar.

5 Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

15 1. In a road grader, the combination with a vehicle frame, of a drawbar flexibly connected at its forward end to said frame, a moldboard carried by said drawbar, longitudinal rock shafts, mechanism for supporting said rock shafts on the rear portion of said frame, crank arms on the forward ends of said rock shafts, hangers connecting said crank arms to opposite sides of the rear portion of said drawbar, mechanism for for rocking said shafts individually to effect adjustment of the moldboard relative to said frame, upright counterbalancing springs at the sides of said frame, mechanism projecting laterally from the bottom of said frame for anchoring the lower ends of said springs, segmental sheaves secured to said rock shafts to rotate therewith, and flexible connections between said segmental sheaves and the upper ends of said springs respectively located between its adjacent rock shaft and the frame in position to enable the springs to counterbalance a part of the weight of the drawbar and moldboard.

20 2. In a road grader, the combination with a vehicle frame, of a drawbar flexibly connected at its forward end to said vehicle frame, a grader blade carried by said drawbar, spaced-apart rock shafts mounted at the sides of said vehicle frame, radial arms at the forward ends of said rock shafts, hangers connecting said arms to the sides of said drawbar, grooved cams on said rock shafts, chains connected to said cams and reaved along the grooves thereof, a transverse cross-piece connected to the underside of said frame, upright springs connecting the said cross-piece under said frame to said chains at the inner sides of the rock shafts in opposition to the radial arms to counterbalance the weight exerted by the drawbar and grader blade on said hangers, and means comprising worm gearing connected to said rock shafts for operating the same individually.

25 3. In a road building machine, the combination with a vehicle comprising a supporting frame, of a drawbar connected at its front end to said frame, a moldboard carried by said drawbar, spaced-apart extensible hangers each comprising a rod connected to said drawbar and slidably through a relatively short tube, a rock shaft mounted in the rear portion of said supporting frame, a depending crank arm at the forward end of said rock shaft, a link connecting said crank arm to either one side or the other of the rear end portion of said drawbar, means for holding the hangers at adjusted lengths one relatively long and the other relatively short, mechanism on said supporting frame connected to said hangers to individually actuate the same, and means for rocking said shaft at least 180° to laterally shift the drawbar for co-operation with the actuation of the hangers to effect adjustment

of the moldboard in steep bank sloping position at either side of the machine.

4. In a road grader, the combination with a vehicle frame, of a drawbar flexibly connected at its forward end to said frame, a moldboard carried by said drawbar, longitudinal rock shafts, mechanism for supporting said rock shafts on said frame, crank arms on the forward ends of said rock shafts, hangers connecting said crank arms to opposite sides of the rear portion of said drawbar, mechanism for rocking said shafts individually to effect adjustment of the moldboard relative to said frame, upright elongated counter-balancing springs adjacent the sides of said frame, mechanism for anchoring the lower ends of said springs to the rear end portions of said frame, and mechanism for connecting the upper ends of said springs to said rock shafts to effect decreased leverage as the tensions in said springs increase when the drawbar and moldboard are adjusted to predetermined positions.

5. In a bank sloping machine, the combination with a wheeled supporting frame, of a drawbar frame, a road-working implement carried by said drawbar frame, spaced-apart rock shafts mounted on said frame, crank arms at the forward ends of said rock shafts, extensible hangers connecting said crank arms to said drawbar frame, each hanger comprising a tube associated with a rod capable of extending entirely through the same, a third rock shaft mounted on said frame to extend longitudinally thereof, a crank arm at the forward end of said third rock shaft, a link connecting said last-named crank arm to one side of the rear end of said drawbar, and means for actuating said first-named rock shafts individually with the hangers adjusted to different lengths so as to cooperate with the rocking of said third shaft to adjust the moldboard to steep bank sloping position at one side of the machine.

6. In a bank sloping machine, the combination with a vehicle frame, of spaced apart rock shafts extending along the sides of said frame, crank arms on the forward ends of said rock shafts, a drawbar flexibly connected at its forward end to said vehicle frame, a grader blade carried by said drawbar, extensible hangers connecting said crank arms to the sides of the rear end portion of said drawbar, each of said hangers comprising a rod slidable through a tube, a third rock shaft extending longitudinally along the mid-portion of said vehicle frame, a laterally swinging crank arm at the forward end of said third rock shaft, a link connecting said last-named crank arm to one side of the rear end of said drawbar, and means individual to each rock shaft for rotating each of said crank arms through 180° to effect adjustment of said grader blade to a steep bank cutting position at one side of the machine.

7. In a bank sloping machine, the combination with a vehicle frame, of a drawbar connected at its front end to said vehicle frame, a grader blade carried by said drawbar, spaced-apart extensible

- hangers each comprising a rod connected to said drawbar and slidable through a relatively short tube, a rock shaft mounted in the rear portion of said frame midway between the sides thereof, a depending crank arm at the forward end of said rock shaft, a link connecting said crank arm to one side of the rear end portion of said drawbar, means for holding the hangers at adjusted lengths one relatively long and the other relatively short, spaced-apart rock shafts at the sides of said vehicle frame and extending longitudinally thereof, crank arms connecting the forward ends of said spaced-apart rock shafts to the tubes of said hangers, and means capable of rocking each of the three aforesaid shafts at least 180° to effect laterally shifting of the drawbar for co-operation with the actuation of the hangers to effect adjustment of the grader blade to steep bank cutting position at one side of the machine.
8. In a road grader, the combination with a vehicle frame, of a drawbar flexibly connected at its forward end to said vehicle frame, a grader blade carried by said drawbar, spaced-apart rock shafts mounted at the sides of said vehicle frame, radial arms at the forward ends of said rock shafts, hangers connecting said arms to the sides of the rear end portion of said drawbar, cams secured to said shafts to rock therewith, upright elongated springs, mechanism connecting the lower ends of said springs to said frame, mechanism connecting said cams to the upper ends of said springs to increase the tension in one of said springs when said shafts are rocked to adjust the grader blade to bank-sloping position, and means for rocking said shafts to adjust the elevation of said grader blade against the tensions in said springs.
9. In a road grader, the combination with a vehicle frame, of a U-shaped support secured thereto and comprising upright standards at the sides of said vehicle frame, longitudinal connecting bars between the said upright standards and downwardly sloping beams of the rear portion of said vehicle frame, brackets extending laterally from said vehicle frame, spaced rock shafts journaled to said upright standards and journaled to said brackets to support said rock shafts to extend longitudinally of said vehicle frame, inwardly facing cams on said rock shafts, upright elongated springs, means for connecting the upper ends of said springs to said cams, means for connecting the lower ends of said springs to the lower rear end portion of said vehicle frame, said springs being located adjacent the inner sides of said longitudinal connecting bars, a drawbar flexibly connected at its forward end to said vehicle frame, mechanism comprising hangers connecting said rock shafts to said drawbar, a road-working implement carried by said drawbar, and means supported by said standards for rocking said shafts to effect adjustment of the road-working implement.

FRANKLIN E. ARNDT.
